United States Patent Office.

ROBERT JORDAN ROBERTS, OF NEW YORK, N. Y.

Design No. 4,514, dated December 13, 1870.

DESIGN FOR A SHOW-CASE.

The Schedule referred to in these Letters Patent and making part of the same.

To all whom it may concern:

Be it known that I, ROBERT JORDAN ROBERTS, of the city of New York, in the county and State of New York, have invented a new and original Design for Show-Case; and I do hereby declare that the following is a full, clear, and exact description thereof, which will enable others skilled in the art to make and use the same, reference being had to the accompanying drawing forming part of this specification.

Figure 1 represents a front elevation of my new show-case.

Figure 2 is a horizontal section of the same, *x x*, fig. 1, being the sectional line.

Similar letters of reference indicate corresponding parts.

This invention relates to a new design for a show-case; and

It consists—

First, in the new outline or configuration of the same; and

Second, in the new form and arrangement of shelves therein.

The show-case A is made of a pyramidal form, with glass faces, which are secured in wooden uprights or corner pieces *a a*.

The top of the case is crowned by a projecting cornice *b*, which may be composed of suitable moldings.

Within the show-case is an ornamental post B, set up within the show-case, and provided with a suitable number of horizontal shelves *c c*, of which the upper is made in shape of a cross, as shown in fig. 2, while the lower is of quadrangular or other suitable form.

d d are hooks secured in the under sides of the shelves, but not necessarily.

I claim as my invention—

1. The design or configuration of a show-case, as shown.
2. The design of the ornamental post and shelves *c c*, within the show-case, as shown.

ROBERT J. ROBERTS.
